UNITED STATES PATENT OFFICE.

WILLIAM H. PRITCHARD, OF NEW YORK, N. Y., ASSIGNOR TO PATENT HOLDING COMPANY, OF NEW YORK, N. Y., A CORPORATION OF NEW YORK.

DESIGN FOR A MUSICAL INSTRUMENT.

No. 38,404.

Specification for Design.

Patented Jan. 8, 1907.

Application filed November 28, 1906. Serial No. 345,564. Term of patent 14 years.

To all whom it may concern:

Be it known that I, WILLIAM H. PRITCHARD, a citizen of the United States, residing in the city, county, and State of New York, have invented a new, original, and ornamental Design for a Musical Instrument, of which the following is the specification, reference being had to the accompanying drawings, forming a part thereof.

Figure 1 is a front elevation, and Fig. 2 is a

side elevation, of a musical instrument, showing my design.

I claim—

The original design for a musical instrument, as shown.

WILLIAM H. PRITCHARD.
